POWDERED COAL APPARATUS

Filed July 29, 1919

2 Sheets-Sheet 2

UNITED STATES PATENT OFFICE.

AUBREY J. GRINDLE, OF CHICAGO, ILLINOIS, ASSIGNOR TO GRINDLE FUEL EQUIPMENT COMPANY, A CORPORATION OF ILLINOIS.

POWDERED-COAL APPARATUS.

Application filed July 28, 1919. Serial No. 314,137.

To all whom it may concern:

Be it known that I, AUBREY J. GRINDLE, a citizen of the United States of America, and resident of Chicago, county of Cook, and State of Illinois, have invented certain new and useful Improvements in Powdered-Coal Apparatus, of which the following is a specification, and which are illustrated in the accompanying drawings, forming a part thereof.

10 The invention relates to apparatus for the use of powdered coal as a fuel and has special reference to the provision of an improved carbureter or mixing device for procuring uniformity in the mixture of air and 15 comminuted fuel and adjusting the velocity of flow of the same to give best results when supplied to a jet burner. The principal object of the invention is therefore to provide apparatus for insuring such regularity in 20 the relative amounts of air and fuel in the combustible mixture and the required rate of delivery of the same to the burner for obtaining a continuous flame of uniform intensity.

25 In the accompanying drawings;

Fig. 1 is a plan view, partially in section, showing the improved carbureter and an associated burner separated from other parts;

Fig. 2 is a side elevation of the apparatus 30 illustrated in Fig. 1, partly in section;

Fig. 3 is an elevation of the apparatus viewed from the discharge end of the burner;

Fig. 4 is an elevation of a detail of the carbureter separated from other parts;

35 Fig. 5 is a detail longitudinal sectional view of the carbureter taken on the line 5—5 of Fig. 1;

Fig. 6 is a vertical longitudinal sectional view of a melting furnace with which the 40 improved form of carbureter may be used, a plurality of the carbureters and one of the associated burners being shown in elevation, while a second burner is shown in section;

Fig. 7 is a sectional view similar to a detail of Fig. 2, but showing a modified form 45 of construction; and

Fig. 8 is a detail sectional view taken on the line 8—8 of Fig. 6.

In the apparatus illustrated for the purpose of disclosing one embodiment of the invention, the conduits 47 and 88 may be of considerable length and may have a mixture of air and powdered fuel fed there-

through by suitable apparatus, the mixture being given a high velocity in order that 55 the air may successfully carry the fuel with it. Each of the said conduits delivers to the corresponding burner 60 or 89 through a carbureter 58 or 90 which forms the subject of the accompanying claims.

60 Carbureter 58 is preferably circular in cross section at the end adjacent the conduit 47 to which it is connected, and increases in size toward its opposite end where it is flattened to rectangular shape, the rectangular 65 portion being of uniform cross sectional area and of approximately twice the cross sectional area of the conduit 47. Delivery of the mixed fuel and air to the associated burner 60 at relatively low velocity is thus 70 obtained while still maintaining a high velocity for the charge through the said first mentioned end portion of the carbureter.

The carbureter 58 preferably also includes a mixing device generally designated 75 80, illustrated in detail in Figs. 4 and 5. Preferably the smaller tubular portion of the carbureter shell is of uniform cross sectional area for a portion of its length to receive a ring 53 which fits closely within the 80 shell and is removably held in place therein as by set screws, one of which is shown at 52. Within the ring 53 are mounted two oppositely inclined sets of stationary deflecting blades 54, 55. As shown, the two sets 85 of blades 54, 55, are concentrically arranged at different distances from a central hub 56, the effect of the blades being to tend to rotate the axial and the surrounding portions, respectively, of the blast of mixed air and 90 fuel in opposite directions and thereby insure the greatest uniformity in the mixture. Location of the mixing device 80 in the said smaller tubular portion of the carbureter shell contemplates the agitation of the blast 95 of mixed air and fuel by the oppositely inclined deflecting blades 54 and 55 while the said blast is still moving at a high velocity, but immediately prior to the reduction of velocity due to the entrance of the blast into 100 the flaring portion of the carbureter shell.

The furnace illustrated in Fig. 6 is specially designed for use as a melting furnace. As shown, it comprises side walls, as 81, a roof 82, and hearth 83. Preferably the hearth 105 83 slopes upwardly adjacent one end of the

furnace, as at 87. This arrangement contemplates that the cold charge to be melted will be heaped upon the lower portion of the hearth, thus leaving the upwardly inclined portion 87 exposed until the charge is melted and the furnace is in full operation. The interior of the furnace may thus be considered as divided into a combustion chamber 85 and a heating chamber 86. The upwardly inclined portion 87 of the hearth then constitutes the floor of the combustion chamber until it is covered by the molten bath. As this portion of the hearth slopes downwardly toward the heating chamber, the melted fuel ash which may collect upon it during the early part of the operation will drain therefrom to mingle with the slag which accumulates upon the melting charge.

While the burner 60 is the only one shown at the front of the furnace, it will be understood that a number of such burners, arranged as desired, may be used. Preferably, each burner comprises an outer chambered shell 61, formed with a circumferential bead 62 for limiting its entrance into the furnace wall and making a tight joint with the margins of the opening, as 42, therein. As the maximum burner opening will not be required at all times, and as it may be desirable to control the direction of the flame within the furnace, a pair of swinging vanes 63, 64, may be mounted within the shell 61. As shown, the swinging vanes 63, 64, are each formed with horizontally directed trunnions 65, 66, at their opposite edges, and a handle, as 67, is applied to one of the trunnions of each of the vanes for its adjustment. Preferably, each of the handles 67 is formed with a lateral projection 68, having a curved slot which receives a clamping bolt 69 for securing the corresponding vane in adjusted position.

To prevent the deleterious action of heat upon the burner, the vanes 63, 64, when employed, are preferably also chambered and provision is made for the circulation of water through the chambers of the burner shell 61 and the vanes. As shown, an inlet water pipe 70 is formed on the shell 61 admitting water to its chamber. From the chamber of the shell 61, the water is conducted, as by means of pipe 71, to the adjacent trunnion 66 of one of the vanes, as 64, all of which trunnions are preferably made tubular with portions extending to the chambers of the corresponding vanes. Two of the trunnions 65, 66, are then connected by pipe 73 (Fig. 3) for the transfer of water from one to the other vane. The remaining trunnion is connected with pipe 74 through which the water is led away. If desired, a series of baffle plates 72 (Fig. 1) may be arranged within the chamber of each vane 63, 64. These baffles are effective to prevent the path of the water being confined to that part of the vane

chamber which is adjacent the inner edge of the vane, whereas this condition might be accompanied with the formation of steam in the remainder of the chamber and melting of the vane along its outer edge.

In the modification shown in Fig. 7, a separate tubular connector or nozzle 76 is interposed between the carbureter 58 and burner 60. This nozzle is formed with a flange 75 at one end which is detachably bolted to a flange 59 at the adjacent end of the carbureter while the other end of the nozzle slips into the burner, its entrance being limited by a circumferential bead 77. The arrangement permits of the parts being readily taken down for inspection or repair, or the nozzle 76 may be renewed, when required, without disturbing the connection between the burner 60 and the furnace wall 81 or water pipes 74.

The carbureter 90 and burners 89 may be of like construction with the carbureter 58 and burner 60, but of different shape, and no adjustable deflecting blades are provided in the burners 89. As shown, the burners 89 project through the roof 82 of the furnace, each burner covering substantially half the width of the furnace and being directed downwardly and forwardly at a suitable angle. If delivery of fuel to the conduits 88 is entirely interrupted, air alone may be introduced through one or both of the burners 89 for supplementing the supply of air for combustion of the fuel delivered through the burner 60, and when so introduced this supplemental stream of air will have the effect of depressing the flame upon the material carried on the hearth 83. On the other hand, mixed air and fuel may be supplied to one or both of the burners 89, when desired to supplement the flame delivered by the burners at the front end of the furnace. While the two burners 89 are shown as being arranged in a common plane, it will be understood that any number of these additional burners may be used and that they may be arranged along the furnace as required.

By a proper manipulation of the vanes 63, 64, of the burner 60, the flame may be directed into any part of the furnace. When a fresh charge of cold iron has been placed upon the hearth 83, it is usually preferable to so adjust the vanes as to cause the blast to impinge upon the then exposed floor 87 of the combustion chamber for heating the same to more readily maintain combustion of the fuel. It is noted, however, that when a uniform admixture of air and fuel is maintained, whereby separate gusts or puffs of flame are avoided, there will be no failure of ignition when the flame has once been started and the deposit of a burning oil soaked rag or the like upon the floor 87 of the combustion chamber at the beginning of the operation will usually be sufficient for

igniting the fuel. Later, in the operation of the furnace, the vanes 63, 64, of the burner 60 may be adjusted to direct the flame into the heating chamber 86. When the furnace 5 is in full operation it may desirable to swing the directing vanes to their open position and the additional burners 89 may also be used.

I claim as my invention:

10 1. In a powdered fuel feeder, in combination, a burner, a circular conduit adapted to have a blast of air and fuel passed therethrough, an expanding connection applied to the delivery end of the conduit for reducing the velocity of said blast and a flattened connection between said expanding connection and said burner.

20 2. In a powdered fuel feeder, in combination, a burner, a conduit of less cross sectional area than the burner inlet opening adapted to have a blast of air and comminuted fuel passed therethrough for delivery to the burner, mixing blades in said conduit, said conduit increasing substantially in 25 size adjacent the burner as compared with its size at the blades whereby the velocity of the blast entering the burner is reduced.

30 3. In a powdered coal apparatus, in combination, a jet burner, a conduit of less cross sectional area than the burner inlet opening adapted to have a blast of air and comminuted solid fuel passed therethrough for delivery to the burner, and means for reducing the velocity of said blast at the burner 35 comprising a flaring connection between the conduit and the said burner.

40 4. In a powdered coal apparatus, in combination, a jet burner, a conduit connected to the burner and being of uniform cross sectional area substantially less than the area 45 of the burner inlet opening throughout the major portion of its length and expanding to the size of the burner inlet opening immediately adjacent the burner, adapted to have a blast of air and comminuted solid fuel passed therethrough and a set of mixing blades mounted within the smaller part of the conduit immediately adjacent the said expanding portion of the same.

50 5. In a powdered coal apparatus, in combination, a burner, a conduit adapted to carry a blast of air and fuel leading thereto, and comprising a cylindrical portion for the portion of its length remote from the burner, 55 and of rectangular shape having twice the cross-sectional area of the said cylindrical

portion at the end adjacent the burner opening.

6. In a powdered coal apparatus, in combination, a burner, a tubular conduit leading to the burner and adapted to carry a blast of air and comminuted fuel, said conduit being of cylindrical form for a portion of its length adjacent the end remote from the burner, and of rectangular shape having greater cross-sectional area than the said cylindrical portion at the end adjacent the burner opening, and an annular series of stationary inclined blades mounted within the cylindrical portion of said conduit section. 65

7. In a powdered coal apparatus, in combination, a burner, a tubular conduit section leading to said burner for conveying the blast of air and comminuted fuel of cylindrical form for a portion of its length remote from said burner and of rectangular shape having greater cross sectional area than the said cylindrical portion at the end adjacent the burner opening and a mixing 75 device removably mounted within the said cylindrical portion of the conduit section comprising a ring which fits closely within the said cylindrical portion of the conduit section and an annular series of stationary inclined deflecting blades mounted within and carried by the said ring. 80

8. In a powdered coal apparatus, in combination, a burner, a tubular conduit section leading to said burner for conveying the blast of air and comminuted fuel of cylindrical form for a portion of its length remote from said burner and of oblong rectangular shape having greater cross sectional area than the said cylindrical portion 95 at the end adjacent the burner opening, and a mixing device removably mounted within the said cylindrical portion of the conduit section comprising a ring which fits closely within the said cylindrical portion of the conduit section and an annular series of stationary inclined deflecting blades mounted within and carried by the said ring, the diameter and width of the said ring being respectively less than the longer and 100 shorter dimensions of the said oblong rectangular end of the conduit section to permit insertion and removal of the said mixing device through the said oblong rectangular end of the conduit section. 105

AUBREY J. GRINDLE.
